CLAIM

The ornamental design for a double row seven day pill box, as shown and described.

DESCRIPTION

FIG. 1 is a top and front perspective view of a double row seven day pill box showing our new design;

FIG. 2 is a front view thereof;

FIG. 3 is a rear view thereof;

FIG. 4 is a left side view (viewer's perspective) thereof;

FIG. 5 is a right side view (viewer's perspective) thereof;

FIG. 6 is a top view thereof; and,

FIG. 7 is a bottom view thereof.

The broken lines depict portions of the double row seven day pillbox that form no part of the claimed design.
